UNITED STATES PATENT OFFICE

2,607,461

COIN SELECTOR

William Patzer, Chicago, Ill., assignor to Clarence E. Threedy, Chicago, Ill., as trustee

Application January 9, 1947, Serial No. 721,017

1 Claim. (Cl. 194—1)

1

This invention relates to certain new and useful improvements in coin selectors.

More particularly, this invention constitutes an improvement over that shown and described in Letters Patent No. 2,326,673 granted on the 10th day of August, 1943, and has reference to a new and novel arrangement for the acceptance of two coins, either of the same denomination or of different denomination, whereby to effectuate actuation of an associated mechanism in the operation of the machine of which my improved coin selector is a part.

My improved coin selector is especially adaptable for association with coin-controlled machines such as vending machines or the like, in which the latter requires for its operation the deposit of at least two coins. In this phase of the invention, an object is to provide in a selector two independent coin pathways having arranged therein, in juxtaposition with respect to each other, a coin blocking member interlatched with a latch control arm therefor with said blocking member adapted to block the passage of the coin through the pathway with which it is associated until released from interlatched relation with respect to the said latch member by a coin striking and pivoting such latch member in its descent down the coin pathway with which said latch member is associated.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a fragmentary side elevational view of a coin selector showing my invention associated therewith;

Fig. 2 is a fragmentary side elevation view similar to Fig. 1 but showing the blocking member therein illustrated disposed for movement to coin-releasing position;

Fig. 3 is a side elevational view similar to Fig. 2 showing the blocking member in coin-releasing position;

Fig. 4 is a fragmentary side elevational view partly in section of the reverse side of the illustration in Fig. 1;

Fig. 5 is a perspective view of one of the coin blocking members;

Fig. 6 is a perspective view of the other of the coin blocking members; and

Fig. 7 is a fragmentary sectional detail view taken substantially on line 7—7 of Fig. 1.

As the improvements constituting the subject

2

matter of this invention are preferably incorporated in a coin selector fully shown and described in Letters Patent No. 2,326,673 hereinbefore mentioned, only so much of that coin selector is illustrated and described herein, as is thought necessary for a full and complete understanding of the extent of my improvements and the accomplishment thereof.

In this connection, the coin selector is indicated 10 generally at 10 and includes a wall 11 from which extend lateral flanges 12 by means of which the selector is mounted in place in a manner well known in the art.

One side of this wall 11, as shown in Figs. 1 to 3 15 inclusive, provides a coin pathway 13, down which coins gravitate along a suitable track 14. This coin pathway 13 terminates into an exit opening 15 from which the coins drop for passage into engagement with associated mechanism (not 20 shown) controlled by such coins.

On the opposite side of the wall 11, by means of a channel-shaped member 16, there is provided, together with the wall 11, a coin pathway 17, also having a coin exit 18 from which coins drop for 25 passage into engagement with the aforesaid associated mechanism.

In this coin pathway 17 is a latch arm 19. This latch arm 19 is pivoted as at 20 to the wall 11 to one side of a longitudinal axis therethrough, whereby to cause the arm 19, by virtue of its own 30 weight, to assume the position shown in Fig. 1 within the pathway 17.

This latch arm 19 has an angled end portion 21 normally inclined with respect to the vertical axis of the pathway 17, whereby a coin descending 35 the pathway 17 will strike the end portion 21 of the latch arm 19 and pivot the arm 19 in a clockwise direction, as viewed in Fig. 4.

The latch arm 19 has an extended portion 22, and carried by this extended portion 22 is a latch 40 pin 23 operable in an arcuated slot 24 formed in the wall 11.

Arranged in the pathway 13 is a blocking arm 25 having an edge portion 26 thereof curved to substantially conform to the curvature of a coin 45 N. The upper end portion of the arm 25 provides a pair of spaced fingers 29 and 30, the space between which provides the slot 31 into which normally engages the pin 23. This arm 25 is pivoted to the wall 11 by means of a pintle 27, and to one 50 side of this pintle 27, the arm 25 is enlarged to provide a counter-weight 28 whereby to maintain the arm 25 normally in the position shown in Fig. 1, a position in which the arm 25 is ready to pivot under action of the counter-weight 28 55 from the position shown in Fig. 1 to that illus-

trated in Fig. 2, upon movement of the latch pin 23 from its position in the slot 31.

The latch arm 19 and the blocking arm 25 normally are in the position shown in Fig. 1.

Assuming that the coin selector 10 is designed to receive a penny P and a nickel N as the requirement for operating associated mechanism (not shown), a penny P, descending the coin pathway 17, will strike the inclined angular portion 21 of the latch arm 19 and the weight of the penny P plus its momentum will cause the latch arm 19 to pivot clockwise, as viewed in Fig. 4. This pivotal movement of the latch arm 19 will disengage the latch pin 23 from the keeper slot 31, permitting the blocking arm 25, by action of its counter-weight 28, to pivot in an anti-clockwise direction, as viewed in Fig. 2, to a position where the finger 30 will be disposed beneath the latch pin 23. A nickel N descending down the coin pathway 13 will strike the blocking arm 25 and with micro-speed action pivot this blocking arm 25 in a clockwise direction against the action of the counter-weight 28, to the position shown in Fig. 3, which position of the blocking arm 25 permits the passage of the nickel N through the exit 15.

Assuming that instead of starting the foregoing operation by means of a penny, the nickel N first descends through the selector. As this nickel N descends through the coin pathway 13, it will strike against the arm 25, but as this arm 25 is latched against pivotal movement, as shown in Fig. 1, by the latch pin 23 engaged in the keeper slot 31, pivotal movement of the arm 25, to allow passage of the nickel N, will be restrained until the pin 23 is disengaged from the keeper slot 31. This is accomplished by means of a penny P striking the angled end portion 21 of the latch arm 19 during the descent of the penny down the coin pathway 17. As the penny P engages this angled end portion 21, the latch arm 19 is caused to pivot with microspeed action in a clockwise direction, as viewed in Fig. 4, moving the latch pin 23 from the keeper slot 31 and allowing the blocking arm 25 to be pivoted under the weight of the nickel N to coin discharge position, as shown in Fig. 3.

Thus, from the foregoing, it is obvious that regardless of the number of coins descending the coin pathway 13, they will be withheld from engagement with associated mechanism which the coins are intended to operate until a coin has descended the coin pathway 17 and effected pivotal movement of the latch arm 19, under which latter condition a coin in the pathway 13 will then be permitted to move through the exit 15.

In vending machines, for example one requiring coins of different denomination for the vending operation, my invention will be especially useful. For example, if the operation of such vending machine requires for its operation the deposit of coins, the total sum of which amounts

to six cents (6¢), my coin selector will not permit the operation of the machine until both coins have been deposited in the selector. My invention is capable of many adaptations and I do not limit the same to vending machines.

While I have used for illustrating the operation of my invention, a nickel and a penny, it is obvious that the denomination of the coins may be the same or different denomination from those of a nickel and a penny.

While I have illustrated and described the preferred form of construction for carrying my invention into effect, this is capable of variation and modifications without departing from the spirit of the invention. I, therefore, do not wish to be limited to the precise details of construction set forth, but desire to avail myself of such variations and modifications as come within the scope of the appended claim.

Having thus described my invention, what I claim as new and desire to protect by Letters Patent is:

A coin selector providing a body having separate adjacent coin pathways, a blocking member pivotally carried by the body and having an end portion thereof projecting into one of said pathways in the path of a coin descending said one pathway, said blocking member opposite said portion having a pair of spaced projections providing therebetween a keeper slot, a blocking arm pivotally carried by the body and having a portion thereof arranged in the other pathway in the path of coins descending said other pathway, said arm having opposite said portion thereof a laterally extending pin normally positioned between said projections in said keeper slot to releasably latch the blocking member against pivotal movement by a coin descending said one pathway, said pin movable by pivotal movement of said arm from engagement in the keeper slot into engagement with and upon one of said projections to release the blocking member for pivotal movement by a coin descending said one pathway, and separate counterbalance means for pivoting said blocking member and said blocking arm into coin blocking position in said pathways.
